GAS CARTRIDGE TYPE PNEUMATIC TIRE INFLATOR

Fumio Ishigaki, Kawasaki-shi, Kanagawa, Tsuneharu Chiba, Kitamoto-shi, Saitama, Muneo Yokoyama, Yachiyo-shi, Chiba, and Mutsuo, Hirano, Tokyo, Japan, assignors to Nippon Piston Ring Co., Ltd., Tokyo, Japan

Filed Aug. 27, 1975, Ser. No. 608,358

Claims priority, application Japan Apr. 4, 1975

Term of patent 14 years
The term of this patent subsequent to Oct. 19, 1990,
has been disclaimed

Int. Cl. D9—01

U.S. Cl. D9—8

FIG. 1

FIG. 2

FIG. 3

FIG. 4

FIG. 5

FIG. 6

FIG. 1 is a top front perspective view of a gas cartridge type pneumatic tire inflator showing our new design;
FIG. 2 is a bottom rear perspective view thereof;
FIG. 3 is a front elevational view thereof;
FIG. 4 is a rear elevational view thereof;
FIG. 5 is a top plan view thereof; and
FIG. 6 is a bottom plan view thereof.
We claim:

The ornamental design for a gas cartridge type pneumatic tire inflator, as shown.
